SHORT RANGE BULLET

Filed May 26, 1931

FIG - 1 -

FIG - 2 -

INVENTOR.
John Matthews
BY W.N. Roach
ATTORNEY

UNITED STATES PATENT OFFICE

JOHN MATTHEWS, OF PHILADELPHIA, PENNSYLVANIA

SHORT RANGE BULLET

Application filed May 26, 1931. Serial No. 540,066.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to bullets and more particularly it has reference to a short-range, practice bullet.

10 The principal considerations governing the design of a practice bullet are accuracy of flight, a trajectory conforming throughout its short range to that of the service bullet, and cheapness of manufacture.

15 In meeting these requirements the bullet forming the subject of the present invention is characterized by a hollow body having a closed base and an open nose.

20 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

25 A practical embodiment of the invention is illustrated in the accompanying drawing, in which,

30 Fig. 1 is a view in side elevation of the improved bullet and

Fig. 2 is a longitudinal sectional view thereof.

Referring to the drawing by numerals of reference:

35 The bullet consists of a hollow body 5 whose external dimensions are substantially identical with a service bullet, on which it is patterned.

40 The tapered nose 6 is cut off to establish an aperture 7 having a diameter equal to approximately one-third of the internal diameter of the body. The wall defining the aperture is internally beveled as at 8 to provide a flared mouth and sharp rim 9 adapted 45 to facilitate the flight of the bullet through the air.

The rear end of the body is closed by a base 10 of approximately twice the thickness of the wall of the body, and pressed inwardly 50 as at 10a to give greater strength.

The rear portion *a*—*b* of the body in rear of the cannelure 11 has a diameter slightly in excess of the remaining portion in order to provide a bearing for taking the rifling of the gun barrel. The bearing is substantially 55 one-half caliber in length and this is one-half of the length of the bearing in the service cartridge. The effect is to reduce wear of the gun barrel and also by reducing the resistance of the bullet in the barrel permit 60 the employment of a smaller propellant charge.

The bullet is preferably formed of gilding metal and has a weight of approximately 35 grains for the .30 caliber size. As constructed 65 its trajectory closely follows the trajectory of the service cartridge up to about 300 yards. Variations in the effective range may be controlled by varying the weight of the bullet and in the propellant charge.

70 Except for the closed base and the open nose, which two features are provided to afford retardation in flight, the improved practice bullet is similar to the jacket of the service bullet and accordingly it may be 75 formed in the same manner.

I claim:

1. A bullet comprising a hollow body, a closed base for the body having a thickness substantially double the thickness of the 80 body, and a tapered nose cut off to form an aperture with a flared mouth and having a diameter substantially one-third the diameter of the body, and the rear portion of the body being enlarged to form a bearing approximately one-half caliber in length.

2. A one piece bullet comprising a hollow body having a short bearing at its rear end and a fixed closed base of greater thickness than the body, a portion of said base indented 90 to afford strength to the bearing.

3. A practice bullet comprising a thin walled hollow body, a closed base for the body having a thickness substantially double the thickness of the walls of the body, an elongated tapered nose cut off to form an aperture, and the rearmost portion of the body enlarged to form a bearing.

JOHN MATTHEWS.
